CLAIM

The ornamental design for a tyre, as shown and described.

DESCRIPTION

FIG. 1 is a perspective view of a tyre in accordance with our new design;

FIG. 2 is a front elevation view thereof; and,

FIG. 3 is a right side view thereof, the left side view being a minor image thereof.

The part of the drawings shown with a reduced tonal value, along with the broken-line perimeter, illustrates a portion of the tyre that forms no part of the claimed design.

The text and symbol adjacent thereto form no part of the claimed design.
